DESIGN FOR A SHOE

Frank V. Grubs, New Rochelle, and Albert Glessner and Morris Schindelman, Brooklyn, N. Y.

Application December 5, 1939, Serial No. 88,700

Term of patent 3½ years

To all whom it may concern:

Be it known that we, Frank V. Grubs, Albert Glessner, and Morris Schindelman, residing respectively at New Rochelle, county of Westchester, State of New York; at Brooklyn, county of Kings, State of New York; and at Brooklyn, county of Kings, State of New York, have invented a new, original, and ornamental Design for Shoes, of which the following is a specification, reference being had to the accompanying drawing, forming a part thereof.

Fig. 1 is a plan view of the shoe showing our new design;

Fig. 2 is a side view of the shoe showing our new design; and

Fig. 3 is a front view of the shoe showing our new design.

The essential features of our design reside in the parts shown in full lines.

We claim:

The ornamental design for a shoe, substantially as shown and described.

FRANK V. GRUBS.
ALBERT GLESSER.
MORRIS SCHINDELMAN.
